Filed Sept. 15, 1959, Ser. No. 57,558

Term of patent 14 years

(Cl. D16—2)

The figure is a top perspective view of a rack and frame combination for supporting paper strips in descending chromatography showing my new design.

The dominant features of my design reside in the full-line portions of the drawing.

I claim:

The ornamental design for a rack and frame combination for supporting paper strips in descending chromatography, as shown and described.
